DESIGN FOR A SPECTACLE FRAME
OR THE LIKE

Edward M. Splaine, Southbridge, Mass., assignor
to American Optical Company, Southbridge,
Mass., a voluntary association of Massachusetts

Application January 2, 1946, Serial No. 125,228

Term of patent 14 years

(Cl. D57—1)

To all whom it may concern:

Be it known that I, Edward M. Splaine, a citizen of the United States of America, residing at Southbridge, in the county of Worcester and State of Massachusetts, have invented a new, original, and ornamental Design for a Spectacle Frame or the like, of which the following is a specification, reference being made to the accompanying drawings, forming a part thereof.

Fig. 1 is a front elevational view of a spectacle frame showing my new design;

Fig. 2 is a top plan view of the spectacle frame shown in Fig. 1; and

Fig. 3 is a fragmentary side elevational view thereof.

The characteristic features of my design are shown in full lines in the drawing; the outline of

lenses shown in Figs. 1 and 3 are for illustrative purposes only.

I claim:

The ornamental design for a spectacle frame or the like, substantially as shown and described.

EDWARD M. SPLAINE.
